CLAIM

The ornamental design for a drawing compass, substantially as shown and described.

DESCRIPTION

FIG. 1 is a front elevational view of a drawing compass showing our new design;

FIG. 2 is a right side elevational view thereof;

FIG. 3 is a left side elevational view thereof;

FIG. 4 is a bottom plan view thereof; and

FIG. 5 is a top plan view thereof.

The rear of the drawing compass is a mirror image of that shown in FIG. 1.
